UNITED STATES PATENT OFFICE.

HUGO A. HECKER, OF BELLEVUE, KENTUCKY, ASSIGNOR TO THE F. M. WATKINS COMPANY, OF CINCINNATI, OHIO, A CORPORATION OF OHIO.

IRONING-MACHINE.

SPECIFICATION forming part of Letters Patent No. 761,833, dated June 7, 1904.

Application filed June 24, 1902. Serial No. 112,974. (No model.)

To all whom it may concern:

Be it known that I, HUGO A. HECKER, a citizen of the United States, residing in the city of Bellevue, county of Campbell, State of Kentucky, have invented certain new and useful Improvements in Ironing-Machines, of which the following is a full, clear, and exact description, reference being had to the accompanying drawings, forming part of this specification.

My improvements relate to machines for ironing laundry goods of various kinds, and more particularly for ironing wristbands and the like; and the improvements consist of a certain novel construction and arrangement of parts to be hereinafter particularly pointed out and claimed.

In the drawings, Figure 1 is a front elevation of my improved machine. Fig. 2 is a side elevation of same, parts being in section. Fig. 3 is a detail side view of the driving-gear for the ironing-table.

A is a solid and substantial base or frame on which the operating parts of the machine are mounted. Journaled in suitable journal-boxes in this frame is the driving-shaft B, upon one end of which are mounted the loose pulleys C D and the fixed pulley E, which loose pulleys carry two belts running in opposite directions, either of which may be shifted to the fixed pulley to rotate the driving-shaft. Journaled in suitable bearings in the frame above the shaft B is the shaft F, which carries on one end an ordinary hollow steel roller G, which is arranged to be heated by inside gas-burners or in any other suitable way. The journal-boxes of this hollow steel roller are provided with the ordinary spring-pressure devices H for applying spring-pressure to this roller, and the roller is rotated by the train of gears I, J, K, and L from the main driving-shaft of the machine, K being a pinion mounted on the shaft M, journaled in suitable bearings in the frame, while the gear I, mounted on the shaft F, receives its motion from the pinion J, mounted on the shaft M. The roller G bears upon and rotates in contact with the segmental

ironing-table N, which is padded in the usual way.

P is the supporting-standard for the ironing-table N, mounted on a sleeve carried on a suitable pin a, journaled in the bracket b, bolted to the frame A and connected by the tie-bolt c with the support or standard R, carrying the segment-gear S, the standard R 55 being mounted on the sleeve on the pin a, the hubs of the two standards R P being secured to the sleeve by the set-screws d. The segment-gear S is oscillated by the pinion U, mounted loosely on the driving-shaft B and 60 rigidly connected with the gear W, mounted loosely on the same shaft and meshing with the pinion Y on the outer end of the shaft M.

A' is a belt-shifter adjustable at any angle for the angle of the belts by the set-screw e, 65 carrying the fingers f, for shifting the belts. The inner end of this belt-shifter, which, it will be understood, is loosely mounted on the driving-shaft B, carries the pin g, which engages the bifurcated end of the shifting-lever 70 B', which shifting-lever is keyed to the rock-shaft h, upon which shaft is also mounted the bell-crank lever C'. The upper end of this lever C' is coupled to the frame by the coiled spring l, secured to the lever and to the adjustable eyebolt m on the frame. The other end of the bell-crank lever is coupled by the connecting-rod D' with the foot-treadle E', pivoted near the base of the frame.

n is a latch which engages the upper end of 80 the bell-crank lever C' to lock same when the machine is not in use. When this latch n is released and thrown back out of the way of the bell-crank lever C', the coiled spring l will oscillate the rock-shaft h and with it the 85 shifting-lever B' to shift the belt-shifter and throw the outermost belt onto the fixed pulley E. The belts are so arranged that by this operation the shaft B and the train of gears L K Y W U will be rotated so as to carry 90 the segment-gear S toward the operator or in the direction of the arrow in Fig. 2. By pressing down on the foot-lever E' the belts will be shifted in the other direction, which

will rotate the driving-shaft in the opposite direction and cause the segment-gear S to move away from the operator. The oscillation of the segment-gear S will oscillate the ironing-table N in contact with the rotating heated roller G, as will be readily understood.

In order that the segment-gear S in the starting of the machine may not travel out of reach of its actuating-pinion U, I provide a loose tooth *p* at the farther end of the segment-gear, pivoted to the gear-frame at *r* and kept in position by the weight *s* or by a suitable spring. As the pinion U is rotated in the direction shown by the arrow in Fig. 3 this loose tooth *p* is merely pressed out of the way, and the segment-gear itself is held in position with the last gear-tooth just clearing the teeth of the pinion by the contact of the set-screw *t*, mounted on an arm *u* on the segment-standard R, and which contacts with the lug *w* on the bracket *b*, attached to the frame. Now when the belts are shifted to oscillate the segment-gear away from the operator the teeth of the pinion U take hold first of the loose tooth, which is so shaped as not to slip when the pinion is moving in this direction. In this way the segment-gear is always in position for oscillation. In order to automatically return the segment-gear at the end of its throw, I secure the lever F' to the rock-shaft *h* and arrange for the arm *y'* on the segment-standard R to contact with this lever F' to oscillate the shaft *h* and shift the belts to change the rotation of the driving-shaft. In order to permit the return of the segment-gear or to reverse the rotation of the driving-shaft either automatically or by the spring *l*, the pressure of the operator's foot upon the treadle E' should be removed.

The operation of the machine will be evident from the foregoing description. The operator releases the rock-shaft *h* by throwing back the latch, and the coiled spring at once shifts the outer belt to the fixed pulley and the driving-shaft with its train of gear oscillates the ironing-table toward the operator until the stop is reached, in which position the last fixed tooth of the segment-gear will just clear the teeth of the operative pinion, and under the further rotation of the driving-shaft the loose tooth will play back and forth. Placing the article to be ironed upon the ironing-table, the operator presses down the foot-lever, which at once shifts the belts to rotate the driving-shaft in the opposite direction, oscillating the ironing-table away from the operator until the arm on the opposite side of the segment-gear support strikes the supplemental lever on the rock-shaft *h*, when the belts will be again shifted and the ironing-table returned to its original position. At the same time that the ironing-table is actuated it will be understood that the train of gear from the driving-shaft also

rotates the ironing-roller in the proper direction. It will also be seen that the coiled spring always tends to shift the belts so as to actuate the ironing-table toward the operator and that by pressing the foot-lever the direction of the ironing-table is changed, so that if the operator desires the ironing-table can be oscillated back and forth without completing its full stroke by pressing on the foot-lever as often as may be desired. It will be also noticed that the segment-gear for driving the ironing-table is placed to one side of the ironing-table and that the ironing-table and ironing-roller are entirely free and open on one side, so that articles like wristbands on shirts and other parts attached to the goods can be ironed without passing the entire garment or article through the ironing devices. Thus my machine is specially adapted for this purpose, although of course the entire article can also be treated to the ironing process.

Having thus described my invention, what I claim, and desire to secure by Letters Patent, is—

1. In an ironing-machine the combination with a reciprocating segmental ironing-table, of a segment-gear and standard therefor rigidly connected with said table, means for reciprocating said segment-gear, a lug on the machine-frame and an arm on the segment-gear standard adapted to engage said lug to limit the movement of the table in one direction.

2. In an ironing-machine the combination with a reciprocating segmental ironing-table, of a segment-gear and standard therefor rigidly connected with said table, means for reciprocating the segment-gear, a lug on the machine-frame, an arm on the segment-gear standard, and a set-screw on the said arm adapted to engage said lug to limit the movement of the table in one direction.

3. In an ironing-machine, the combination with a segmental ironing-table, of a segment-gear and standard therefor, a driving-shaft and pinion thereon engaging said segment-gear, loose and fixed pulleys on said shaft adapted to engage oppositely-moving belts, a belt-shifter, a rock-shaft connected therewith, a foot-lever to actuate the rock-shaft in one direction, a supplemental lever on said rock-shaft, and an arm on the segment-gear standard adapted to contact with said lever to automatically shift the belt-shifter and reverse the movement of the segment-gear.

4. In an ironing-machine, the combination with a segmental ironing-table, of a segment-gear and standard therefor, a driving-shaft and pinion thereon engaging said segment-gear, loose and fixed pulleys on said shaft adapted to engage oppositely-moving belts, a belt-shifter, a rock-shaft connected therewith, a bell-crank on said rock-shaft, a spring and foot-lever adapted successively to act upon

said bell-crank to shift the belt-shifter in opposite directions, a supplemental lever on said rock-shaft and an arm on the segment-gear standard to contact with said supplemental lever to automatically shift the belt-shifter and reverse the movement of the segment-gear.

5. In an ironing-machine, the combination with a segmental ironing-table, a segment-gear for reciprocating said table connected therewith, a pinion meshing with and actuating said segment-gear, a cut-away portion at the end of said segment-gear, a tooth pivoted therein adapted to be depressed by the pinion when rotating in one direction and means for 10 maintaining the position of said tooth to be engaged by the pinion when rotating in the opposite direction.

6. In an ironing-machine, the combination with a segmental ironing-table, a segment-gear for reciprocating said table connected therewith, a pinion meshing with and actuating said segment-gear, a cut-away portion at the end of said segment-gear, a tooth pivoted therein and adapted to be depressed by the pinion when rotating in one direction, means 20 for maintaining the position of said tooth to be engaged by the pinion when rotating in the opposite direction and means for preventing the segment-gear being thrown out of position to be engaged by said pinion.
